CLAIM

The ornamental design for a nasal cannula for a nasal interface, as shown and described.

DESCRIPTION

FIG. 1 is a top, front and left-side perspective view of a first embodiment of a nasal cannula for a nasal interface, showing our new design;

FIG. 2 is a front view thereof;

FIG. 3 is a rear view thereof;

FIG. 4 is a right-side view thereof;

FIG. 5 is a left-side view thereof;

FIG. 6 is a top view thereof; and

FIG. 7 is a bottom view thereof.

FIG. 8 is a top, front and left-side perspective view of a second embodiment nasal cannula for a nasal interface, showing our new design;

FIG. 9 is a front view thereof;

FIG. 10 is a rear view thereof;

FIG. 11 is a right-side view thereof;

FIG. 12 is a left-side view thereof;

FIG. 13 is a top view thereof; and,

FIG. 14 is a bottom view thereof.

The dash-dash broken lines are used to illustrate portions of the nasal cannula for a nasal interface that form no part of the claimed design.

1 Claim, 14 Drawing Sheets
